UNITED STATES PATENT OFFICE.

KONSTANTIN VON OLSZEWSKI, OF DRESDEN, GERMANY.

TIN-OXIDIZING FURNACE.

1,028,595.

Specification of Letters Patent.

Patented June 4, 1912.

Application filed October 27, 1911. Serial No. 657,161.

To all whom it may concern:

Be it known that I, KONSTANTIN VON OLSZEWSKI, a subject of the Emperor of Germany, and a resident of Dresden, Germany, have invented certain Improvements in Tin-Oxidizing Furnaces, of which the following is a specification.

The present invention relates to improvements in furnaces of the kind employed for the oxidation of tin, and consists in the provision of a divided fire chamber in connection with a particular air inlet with regulating damper for supplying air to the discharge flue.

By the provision of a divided fire chamber, in each half of which the stoking can take place while the combustion is going on uninterrupted in the other and while the draft in the flue and thereby the temperature of the furnace is being regulated by admitting air to the flue, a detrimental formation of soot and a reduction of temperature during the stoking process, are effectively prevented. A complete and uniform oxidation of the metal is thereby effected, and a perfectly white and soft tin oxid is obtained.

In the accompanying drawings the invention is illustrated, Figure 1 representing a vertical section of the furnace on the line C—D of Fig. 2 which is a section on the line A—B of Fig. 1. Fig. 3 is a horizontal section on the line E—F of Fig. 2.

The metal is disposed in a melting pan *b* which is heated in known manner, the oxidized metal being raked off over an inclined surface *c* into a collecting receptacle *d*.

According to the invention the fire chamber is divided by means of a partition *a* into two halves which are stoked alternately. Between the melting pan and the chimney an air chamber *e* is provided the air supply to which is regulated by means of a damper *f*. While the stoking is in progress the natural draft in the flue, and thereby the temperature of the furnace, can be so regulated by means of the damper *f* that no disturbance whatever in the oxidizing process takes place. The air chamber *e* also prevents oxidized particles from passing off through the chimney together with the flue gases, such passing off and consequent loss of metal being common in the ordinary furnaces.

I claim:

In an oxidizing furnace, the combination with a melting pan and with a furnace for heating the same, of a vertical partition dividing the fire chamber of said furnace into two independent parts, an air chamber arranged between the melting pan and the chimney, and a damper for regulating the air supply to said air chamber, while the parts of the fire chamber are being alternately stoked, so as to maintain the furnace at a uniform temperature, substantially as set forth.

KONSTANTIN VON OLSZEWSKI.
